UNITED STATES PATENT OFFICE.

EDWARD W. SALMON, JR., OF BALTIMORE, MARYLAND, ASSIGNOR TO LEO FESENMEIER,
OF BALTIMORE, MARYLAND.

WALL BRACKET FOR CABINETS.

Application filed August 3, 1922. Serial No. 579,455.

To all whom it may concern:

Be it known that I, EDWARD W. SALMON, Jr., a citizen of the United States, residing in the city of Baltimore and State of Maryland, have invented a certain new and useful Improvement in Wall Brackets for Cabinets, of which the following is a specification.

This invention relates to a supporting means for filing and storing cabinets and has to do particularly with the filing, storage and preservation of motion picture film cabinets.

Motion picture films, both negatives and positives, are composed of highly inflammable material and are particularly susceptible to heat transmitted thereto, either directly or indirectly, and once afire, it is difficult, if not impossible, to extinguish or smother the fire. The films are also susceptible to damage incident to atmospheric conditions. There is not only danger from flames incident to fires, but there is great danger to life, limb and property incident to explosion in the event of fires where motion picture films are stored. It is essential that safe and proper means be provided for the filing and storage of these films. The safety of the public in motion picture houses and buildings in which these picture films are used or stored, has given so much concern to municipalities and to individuals, that it has been found essential to provide and enforce strict legislation to protect the public against the loss of life, limb and property incident to fires and explosions.

Many films cannot be reproduced, and considering the great inherent value of such films, aside from their large earning capacity, and the great monetary loss if destroyed in part or in whole by fire, or through atmospheric or through other conditions or disasters, it is obvious that the value of the films warrants the utmost precaution in the matter of their preservation as well as to guard against the dangers to public and to property.

In the event of falling floors incident to fires, earthquakes, vibrations or other causes, the cabinets and other furniture is precipitated to a floor below or into cellars and at such times, valuable papers and records stored in cabinets are damaged or destroyed because of breakage of the containers due to

frailty of structure, heat, flames and weights of falling timbers and irons.

It is therefore the main object of the present invention to provide a fire proof cabinet for the filing and storage and preservation of moving picture films, either positives or negatives or other valuable records or papers and to support the cabinets on a side wall of the structure in which the cabinets are installed so that in the event of a falling floor from beneath the cabinets or in the event of a falling floor from above the cabinets, the cabinets are sustained against the wall and prevented from being precipitated to a floor or a cellar below, whereby to retain the cabinet intact to preserve the films, records or papers confined therein.

Another object of the invention resides in the provision of a wall support for filing cabinets, embodying among other characteristics, arms so constructed that they can be employed in interchangeable relation in sets for the suspension or support of a plurality of aligning cabinets, and having such relation with the walls of the building and with the cabinets as to sustain the weight of the cabinets to relieve the floors of the entire weight of the cabinets and the contents thereof.

A still further object of the invention resides in the provision of a wall support for filing and storage cabinets comprising supporting elements designed to retain the cabinet against sliding or swinging movement incident to jarring or vibration of the floor, and which is further designed to sustain the weight of the cabinet and its contents to relieve the floor of unnecessary strain.

With the above and other objects in view the invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

Figure 1 is a front elevation illustrating a sectional cabinet supported in accordance

with my invention and also illustrating a sectional unit of another cabinet adjacent thereto.

Figure 2 is a detail perspective view of the invention showing the wall at one side of the support in section.

In carrying out my present invention, I provide a pair of supporting arms, each formed of a single strip of angle iron. The strip of angle iron is bent intermediate its ends to form a vertical attaching portion A, and again bent to form a horizontal supporting portion B. There is thus formed a substantially L-shaped supporting arm having its vertical attaching portion provided with slightly spaced webs 3 and 4 from each of which extend laterally directed flanges 5 and 6, respectively, with the horizontal portions B of each arm and their web portions 7 and 8 aligning with the web portions 3 and 4, and with their flanged portions 9 and 10 aligning with the flanges 5 and 6 of the vertical portions of the arms, the aligning webs of the vertical and horizontal portions of the arms being spaced slightly, as shown.

To strengthen each arm or to brace the horizontal supporting portion of each arm with relation to the vertical wall attaching portion of each arm I provide suitable inner and outer diagonal braces 11 and 12 which have their ends disposed within the spaces between said webs and which are secured therein by means of rivets or other suitable elements 13.

At the point where the strip of angle iron is first bent back upon itself, the webs 3 and 4 take the shape of an eye 14, through which a heavy bolt or other suitable element may be passed into the vertical wall 15, to anchor the respective arm to the wall. Each supporting arm may be further anchored to the wall by additional bolts 16 and 17. Other means for the anchorage of the supporting arms to the vertical wall may be employed if desired. I am simply illustrating one form of securing means, to illustrate the method of carrying out my invention.

The improved supporting means herein described is designed to rest directly upon the floor of a building, and as shown in the accompanying drawings a wood floor 18 is illustrated. Wood floors are often uneven and sometimes sag adjacent the vertical wall, and in such an event the improved supporting means is such that the horizontal supporting portions of the arms will firmly support the cabinet 19 evenly so as to maintain the rear wall of the cabinet in vertical alignment with the vertical wall. By virtue of this method of supporting the cabinet it is sustained in vertical alignment with the vertical wall against the influence of vibrations of the floor.

The even support of the cabinet 19 and

the sustaining of the same against vibration of the floor is due to the right angular relation of the supporting portions of a pair of arms with relation to the vertical portions thereof and to the fact that the cabinet 19 is supported directly upon adjacent inwardly directed flanges 10, as clearly shown in the accompanying drawings, and wherein, in Fig. 1, in particular, it will be seen that the flange 9 of an arm adjacent the flange 10 is designed to support one side of another cabinet disposed thereon and on another flange 10 of an adjacent arm.

In the accompanying drawings, the cabinets are shown of a sectional unit type embracing a base member 20, and a plurality of units mounted thereupon, but it will be understood that the cabinet may be a one piece type of furniture in so far as the supporting means is concerned.

Where a base member 20 is employed, it is detachably secured against lateral movement and the pair of arms are prevented from spreading apart by means of suitable bolts 21 passing through a side of the base 20 and through the respective webs 9 and 10. Where cabinets are arranged side by side, as may be gathered from the illustration in Fig. 1, the bolt 21 may be of such a length as to pass not only through a base 20 and the adjacent webs 7 and 8, but also through the adjacent base 20, whereby to tie both the arms and bases together, against outward sliding movement of the bases or the cabinets and against twisting or lateral movement of the arms as previously explained.

It will thus be understood that if the floor 18 should give way and fall incident to fire, earthquakes or vibrations, that as long as the vertical wall stands, the cabinet is sustained and held firmly against the vertical wall, and that, therefore, wrecking of the cabinet is avoided and the contents preserved irrespective of fire and heat, due to the character of material of which the cabinets are composed, they being composed preferably of non-combustible, non-heat conducting material, and preferably altogether of the character described in my aforesaid copending application.

What is claimed is:

1. A supporting hanger of the character described, comprising an L-shaped arm including spaced web portions throughout its length, each web portion having an outwardly directed flange with the web portions connected together at one end of the arm to provide an attaching eye, and a brace having its ends connected to the arm between the said web portions.
2. A supporting hanger of the character described, comprising an L-shaped arm including spaced web portions throughout its length, each web portion having an out-

wardly directed flange with the web portions connected together at one end of the arm to provide an attaching eye, and inner and outer diagonally disposed braces having 5 their ends connected to the angular portions of the arm between the said web portions.

3. A supporting hanger of the character described, comprising an L-shaped arm including spaced web portions throughout its 10 length, each web portion having an out-

wardly directed flange with the web portions connected together at one end of the arm to provide an attaching eye, and a diagonally disposed brace connecting the angular portions of the arm and having its ends rigidly 15 connected to the angular portions of the arm between the said web portions.

In testimony whereof I have hereunto set my hand.

EDWARD W. SALMON, JR.
